UNITED STATES PATENT OFFICE.

WILLIAM H. YOUNG, OF CHICAGO, ILLINOIS, ASSIGNOR OF ONE-HALF TO
WILLIAM J. MORDEN, OF SAME PLACE.

CABLE-RAILWAY STRUCTURE.

SPECIFICATION forming part of Letters Patent No. 396,638, dated January 22, 1889.

Application filed May 23, 1888. Serial No. 274,846. (No model.)

To all whom it may concern:

Be it known that I, WILLIAM H. YOUNG, a citizen of the United States, residing at Chicago, in the county of Cook and State of Illinois, have invented certain new and useful Improvements in Cable-Railway Structures, of which the following is a specification.

One feature of my invention relates to a chair whereby to secure the rails of a cable-
10 railway track to the yokes, said chair being
adapted to receive and support the rail and
to be clamped to the side extension of the
yoke by means of ratchet-teeth and a locking-
key, the chair being preferably cast in one
15 piece.

In a patent issued to me March 20, 1888,
No. 379,922, a chair is described which is
made of two sections secured together by
bolts. My present construction is an im-
20 provement thereon, inasmuch as I dispense
with the use of these bolts, which are expen-
sive and require time to apply. My present
invention embodies some of the features
25 shown in said patent, particularly those fea-
tures which relate to the support of the base
of the rail; but I have materially modified
said construction by omitting in my present
device a considerable part of the casting, re-
30 taining only such as is serviceable in sup-
porting the rail.

In the drawings, Figure 1 is a perspective
view of a yoke with a rail secured thereto by
means of my improved chair; Fig. 2, an end
35 elevation of the chair, the track-rail being
shown in section. Fig. 3 is a perspective
view of the chair detached.

A is the yoke, which has side extensions,
a a, and the inwardly-arched portions A' A',
which have bolt-flanges a' a', to which the
40 Z-rails, forming the slit, are bolted. In my
present construction the interior of the yoke
is almost circular in form, and I prefer to
employ therein the strengthening-ribs a² a².
This form of yoke affords an unobstructed
45 opening, convenient in the placing of the
cable and sheaves therein. The yoke is cast
in one piece, with the strengthening-ribs so
disposed as to resist lateral strain, and angle-
rails instead of Z-rails may be used, as shown.

With this construction I am able to dispense 50
with the lateral brace-rods shown in my for-
mer patent, and also with the fish-plates com-
monly employed in structures of this sort.

B is the rail, and C the chair. The chair,
as stated, is cast in a single piece and has its 55
base slotted vertically and recessed longitudi-
nally, as shown at b.

D is a rib adapted to receive the web and
head of the rail, so as to support it against
the outward and downward pressure of the 60
car-wheels. A key-seat, d, is cut on the inner
face of that part of the rib D which receives
the web of the rail; and a key may be driven
therein to tighten the rail in its bearings and
prevent movement therein. The chair C is 65
also provided in its base with a dovetailed re-
cess adapted to receive the flanges of the ex-
tensions a of the yoke. One of the walls of
this dovetailed recess is provided with teeth
or corrugations e, and the opposite wall has a 70
key-seat, f. This recess or opening in the
base of the chair is of sufficient width to per-
mit the chair to be slipped over the flanges
of the extension a of the yoke, and one of
said flanges has teeth or corrugations g, cor- 75
responding to those marked e on the chair.

In applying this chair to the securing of a
track-rail to the yokes the base of the rail is
inserted in the recess and slot b and then the
chair is applied to the yoke, the teeth e en- 80
gaging the teeth g, and is secured in proper
position thereon by driving in a key, h, which
can be secured by bending its end over.
From the foregoing description it is apparent
that these yokes are rapidly applied, all bolts 85
are dispensed with, and a chair is provided
which adapts the rails to be laterally ad-
justed upon the yokes. The device may be
made quite light in weight, as in the form
shown the material is so utilized as to secure 90
the necessary strength with due economy of
material. The joint between the track-rails
is formed in the chair, preferably near the
middle of its length—that is to say, the meet-
ing ends of the two rails are inserted in the 95
opposite ends of the chair and abut against
each other at a point midway the length of
the chair. By these means the necessity of

using fish-plates to connect the rails is dispensed with, as the chair secures the ends of the rails permanently in perfect alignment.

I claim—

- 5 1. A railway-chair adapted to receive and support the rail, recessed in its base to receive the yoke, and having corrugations to engage similar corrugations on said yoke, and adapted to be secured thereto by a key, substantially as described.
- 10 2. A railway-chair having in a single casting a base portion adapted to receive the base of the rail, a transverse recess one wall of which is corrugated to adapt it to engage corresponding corrugations of the yoke and the other wall provided with a key-seat, and
- 15

having, also, an upright shoulder or flange to support the web and tread of the rail, substantially as described.

3. A railway-chair consisting of a casting, 20 C, having groove *b*, shoulder *D*, having key-seat *d*, and a base portion having a recess to receive the yoke, one wall of which recess has the corrugations *e* and the other a key-seat, *f*, said walls converging downwardly, whereby 25 to provide a dovetailed joint, substantially as described.

WM. H. YOUNG.
